UNITED STATES PATENT OFFICE.

JEREMIAH HORRIGAN, OF SOLOMON, IOWA.

DRAFT-EQUALIZER.

SPECIFICATION forming part of Letters Patent No. 252,667, dated January 24, 1882.

Application filed September 8, 1881. (No model.)

To all whom it may concern:

Be it known that I, JEREMIAH HORRIGAN, of Solomon, Mills county, Iowa, have invented a new and useful Improvement in Equalizers, 5 of which the following is the specification, reference being had to the accompanying drawings, in which similar letters of reference indicate like parts in both figures.

My invention relates to three-horse equalizers; and its object is to provide an equalizer which shall be light, simple of construction, and easily handled for use.

I attain the objects of my invention by the following method, reference being had to the 15 drawings.

Figure 1 is a top view, and Fig. 2 a back-edge view.

In the drawings, A represents the equalizer-beam or triple-tree, preferably about seven 20 feet long, and tapering toward each end to reduce the weight, and may be about two by four inches in the middle.

On the rear side of the beam A, and at a distance of one-third its entire length from 25 each end, are placed the angle or bell-crank levers B B, each consisting of a long arm, a, and a short arm, b, which may be at right angles to each other. A brace, c, may connect the extremities of the arms a and b in 30 cases where extra strength is required. The bell-cranks B B are inserted in mortised notches in the beam A, and may be prevented from falling out by the pins o, inserted in the angles formed by the arms. The bell-crank levers B 35 B are placed with their long arms toward each other, and may be constructed of flat iron.

From the extremities of the arms a and b of the levers B B extend directly forward through the mortises n and m in the beam A the rods or chains F G H I. Attached to the extremities of the short arms b of the levers B B are the chains C C, extending outward and around the sheaves D D in the extremities of the beam A and forward in the same direction with the rods or chains F G H I. The extremities of 40 the chains C C and of the rods F G H I, terminate in hooks e f g h i j, to which the traces of the horses are hitched directly, the middle horse being hitched to the hooks g h and the side horses to the hooks e f and i j, and since 45 the middle horse exerts one-half its strength on each of the long arms of the levers B it will be equalized by the efforts of the side horses on the short arms of the levers.

The chains C C may be prevented from falling 50 from the sheaves D D by the plates S S passing over the ends of the beam A at a distance from the sheaves not to interfere with the chains freely moving.

What I claim is—

In a three-horse equalizer, the combination 55 of the triple-tree A, provided with the sheaves D D, the angle-levers B B, consisting of the long arms a and the short arms b, and the rods or chains C C F G H I, all constructed and 60 combined to operate substantially as shown, and for the purposes described.

JEREMIAH HORRIGAN.
